UNITED STATES PATENT OFFICE.

DANIEL J. KENNEY, OF DREXEL HILL, PENNSYLVANIA, ASSIGNOR TO GRIFFIN CHOKER ASH TRAY, INC., OF PHILADELPHIA, PENNSYLVANIA, A CORPORATION OF DELAWARE.

DESIGN FOR AN ASH TRAY.

Application filed May 13, 1922. Serial No. 2,213. Term of patent 3½ years.

To all whom it may concern:

Be it known that I, DANIEL J. KENNEY, a citizen of the United States, residing in Drexel Hill, county of Delaware, State of Pennsylvania, have invented a new, original, and ornamental Design for an Ash Tray, of which the following is a specification, reference being had to the accompanying drawing, which forms a part thereof.

The figure is a perspective view of an ash tray embodying my design.

I claim—

The ornamental design for an ash tray as shown.

DANIEL J. KENNEY.
